[57] CLAIM

The ornamental design for a hospital supply cart, substantially as shown and described.

DESCRIPTION

FIG. 1 is an elevational view of a hospital supply cart showing my new design, the opposite side being a mirror image thereof;

FIG. 2 is an end elevational view thereof;

FIG. 3 is an end elevational view thereof opposite to that shown in FIG. 2;

FIG. 4 is a top plan view thereof;

FIG. 5 is a bottom plan view thereof;

FIG. 6 is an enlarged fragmentary vertical sectional view thereof taken along line 6—6 in FIG. 3; and

FIG. 7 is an enlarged fragmentary vertical sectional view thereof taken along line 7—7 in FIG. 4.
